CLAIM

The ornamental design for an enclosure for an electronic device, as shown and described.

DESCRIPTION

FIG. 1 is a perspective view of an enclosure for an electronic device with an x-shaped attachment on the rear face, in accordance with one embodiment of the invention;

FIG. 2 is a front view of the enclosure of FIG. 1;

FIG. 3 is a rear view of the enclosure of FIG. 1;

FIG. 4 is a left view of the enclosure of FIG. 1;

FIG. 5 is a right view of the enclosure of FIG. 1;

FIG. 6 is a top view of the enclosure of FIG. 1; and,

FIG. 7 is a bottom view of the enclosure of FIG. 1.

The broken lines represent environment that form no part of the claim.
